FURNITURE BASE

Donald C. Petitt, New York, N.Y., assignor to Knoll
Associates, Inc., New York, N.Y., a corporation of
New York

Filed Nov. 27, 1963, Ser. No. 77,582

Term of patent 14 years

(Cl. D15—1)

Fig. 1.

Fig. 3.

Fig. 2.

Fig. 4.

Fig. 5.

Fig. 7.

Fig. 8.

FIG. 1 is an elevational view of a furniture base embodying the new design;

FIG. 2 is a plan view, on an enlarged scale, of the furniture base of FIG. 1;

FIG. 3 is a cross-sectional view, on a further enlarged scale, taken on the line III—III of FIG. 1;

FIG. 4 is a cross-sectional view, on a further enlarged scale, taken on the line IV—IV of FIG. 2;

FIG. 5 is a bottom plan view of the base, on the same scale as FIG. 2;

FIG. 6 is an elevational view of the base taken at a different angle from the view in FIG. 1, and on the same scale as FIGS. 2 and 5; and

FIG. 7 is a fragmentary view similar to the central portion of the pedestal of FIG. 6, but on an enlarged scale

and showing a cross-section through the pedestal at the upper end of the fragment.

I claim:

The ornamental design for a furniture base, as shown.
